UNITED STATES PATENT OFFICE.

ROBERT DUGUID, OF THREE RIVERS, QUEBEC, CANADA.

DESIGN FOR A TRICYCLE.

60,223.

Specification for Design.

Patented Jan. 17, 1922.

Application filed March 10, 1921. Serial No. 451,305. Term of patent 14 years.

To all whom it may concern:

Be it known that I, ROBERT DUGUID, a subject of the King of Great Britain, residing at Three Rivers, in the Province of Quebec and Dominion of Canada, have invented a new, original, and ornamental Design for a Tricycle, of which the following is a specification, reference being had to the accompanying drawing, forming a part thereof.

The figure is a perspective view showing my new design.

The object of the present invention is the provision of an ornamental and original design for a tricycle in which the frame thereof comprises straight bars producing straight lines as clearly shown in said drawing.

I claim—

The ornamental design for a tricycle as shown.

ROBERT DUGUID.
